UNITED STATES PATENT OFFICE.

GEORGE WALTER BROOKS, OF MISSOULA, MONTANA.

INTERNAL-COMBUSTION ENGINE.

1,130,060.

Specification of Letters Patent. Patented Mar. 2, 1915.

Application filed July 20, 1914. Serial No. 851,973.

To all whom it may concern:

Be it known that I, GEORGE W. BROOKS, a citizen of the United States, residing at Missoula, in the county of Missoula and State of Montana, have invented certain new and useful Improvements in Internal-Combustion Engines, of which the following is a specification.

This invention relates to internal-combustion engines of the four-cycle type, and its objects are to provide an engine of this type in which a positive scavenging action is obtained, and also to provide a novel and improved valve mechanism. These objects are attained by means of a combination and arrangement of parts to be hereinafter described and claimed, reference being had to the accompanying drawings in which—

Figure 1 is an elevation of the engine, partly in section, Fig. 2 is a vertical cross-section on the line 2—2 of Fig. 1, and Figs. 3 to 7 are diagrams illustrating the cycle of operations.

Referring specifically to the drawings, a four-cylinder engine is illustrated, but it is to be understood that the invention may be applied to other multiple cylinder engines, as well as to single cylinder engines. The cylinders are indicated by the reference character 5, and they are water-jacketed as usual, the water inlet being shown at 6, and the water outlet at 7. The cylinders are mounted on a crank case 8 having bearings 9 at its ends in which the engine crank shaft 10 is supported, said shaft having a fly-wheel 11 as usual. The pistons working in the cylinders are indicated at 12, and the rods connecting the same to the shaft 10 are indicated at 13. In each cylinder 5 also works a reciprocating plunger 14 co-operating with the piston 12 to secure a more complete removal of the exhaust gases, and carrying a novel valve mechanism for controlling the inlet and the exhaust. The plunger 14 is located at the upper or head end of the cylinder, back of the piston 12, and the fuel charge is introduced into the cylinder space between said plunger and the piston and explodes therein to obtain the working stroke of the piston. In the cylinder wall is a recess 15 in which is mounted an igniter 16. This recess opens into the explosion space of the cylinder back of the piston. In that portion of the cylinder in which the plunger 14 works are diametrically opposite inlet and exhaust ports 17

and 18, respectively. The plunger has diametrically opposite ports 19 and 20 opening through its side and positioned to register with the cylinder inlet and exhaust ports, 30 respectively. In the plunger is a cavity 21 in which seats an oscillatory valve 22. The ports 19 and 20 lead to this cavity, and from the latter a port 23 extends and opens through the inner end of the plunger. The port 23 is at the center of the plunger, midway between the inner ends of the ports 19 and 20, and opens into the cylinder space back of the piston. The valve 22 has cavities 24 and 25 spaced from each other and located on opposite sides. In one position of the valve the cavity 24 laps the ports 19 and 23 to admit a fuel charge into the cylinder, and in another position the cavity 25 laps the ports 20 and 23 to allow the spent gases to exhaust. The exhaust is closed when the inlet is open, and when the exhaust is open, the inlet is closed. It will be noted in Fig. 2 that the inner end of the plunger which faces the back or inner end 80 of the piston is concave, and the back of the piston is correspondingly convex.

Behind the plunger 14 is mounted a counter-shaft 26 having a crank which is connected by a short pitman 27 to the plunger, 85 whereby the latter is operated. That portion of the pitman which is connected to the plunger forms the valve 22, the latter being substantially circular in cross section as shown in Fig. 2, and being of such width as 90 to accommodate the cavities 24 and 25 and to cover the ports 19, 20 and 23. The plunger carries a cross-pin 28 which connects the pitman to the plunger, the valve part 22 of the pitman being loose on the pin so that it is 95 free to oscillate.

The upper ends of the cylinders 5 are open and over the same is mounted a housing 29 which incloses the countershaft 26, said housing containing suitable bearings 30 for 100 the countershaft.

On one end of the countershaft 26 is a sprocket wheel 31 which is geared by a chain 32 to a sprocket wheel 33 on the crank shaft 10. The countershaft is thus driven by the crank shaft. A two-to-one gearing is provided so that the countershaft is driven at one-half the speed of the crank shaft.

The engine operates as follows: The crank shafts 10 and 26 rotate in the same direction, 110 the speed of the former being twice that of the latter. It will therefore be evident that

the piston and the plunger travel in opposite directions at times and in the same direction at other times. The valve portion 22 of the pitman 27 also oscillates as the plunger 5 travels up and down. At the end of the exhaust stroke of the piston the plunger is also at the limit of its downward stroke and that portion of the valve 22 which is between the cavities 24 and 25 covers the port 23, and the cavities lap the ports 19 and 20 as shown in Figs. 2 and 3 and at the same time the port 17 registers with the port 19, and the port 18, with the port 20. Now, when the piston starts to travel downward, 10 the valve 22 oscillates in a direction to bring the cavity 24 in position to lap the ports 19 and 23, and a charge is drawn into the cylinder. Fig. 4 shows the intake about to open. When the piston has reached the end 15 of its downward stroke, the countershaft has moved 90 degrees, and while the cavity 24 still laps the ports 19 and 23, the plunger has moved upward through one-half of its travel to cover the port 17, as shown in Fig. 25, thus cutting off the inlet. Also, during the suction stroke the ports 18 and 20 register, and the latter is lapped by the cavity 25, but as the cavity does not lap the port 23, it will be evident that the exhaust is closed. 30 When the plunger has moved upward through one-half of its travel, the port 18 is also covered. The piston now travels upward and compresses the charge trapped between the upper end of the piston and the 35 lower end of the plunger. The plunger continues to travel upward during the compression stroke of the piston until it reaches the limit of its upward travel, leaving a clearance or compression space of about 30 per 40 cent. of the piston stroke. At the end of the compression stroke the valve 22 is at its central position, and the part between the cavities 24 and 25 covers the port 23, and the ports 19 and 20 are also cut off from the corresponding ports 17 and 18, as shown in Fig. 45. Ignition of the charge now takes place and the piston makes its working stroke, and at the same time the plunger makes a downward stroke, but at a less speed, so that when 50 the piston has almost reached the limit of its working stroke, the ports 18 and 20 start to register and the valve 22 has swung to such a position that the cavity 25 laps the ports 20 and 23, as shown in Fig. 7, whereupon the 55 spent gases are allowed to escape. As the piston moves upward on the next, or the exhaust stroke, the plunger continues to move downward until the end of its downward travel, at which time the piston is also at the 60 end of its upward travel, the exhaust remaining open and not closing until the completion of the stroke. The plunger and the piston come close together at the end of the exhaust stroke and thus drive out all the 65 spent gases, there being only a mechanical or

working clearance between the plunger and the piston at this time. This completes the cycle, the herein-described operation being repeated over and over as long as the engine is running. The cylinder is positively scavenged, and a clean incoming charge is assured, resulting in a saving of fuel, positive ignition, and increased power, the charge being completely burned and there being no dead gas in the cylinder. The engine also 70 runs cooler as no exhaust gases remain to heat up the incoming charge prematurely. Greater flexibility is also obtained, as well as a wider range of speeds, as there is a certainty of ignition at a low throttle opening. 80 The parts are completely inclosed and perfect lubrication is therefore possible.

It is to be understood, of course, that the action heretofore described takes place in each cylinder in the proper order. 85

I claim:

1. In an internal-combustion engine, a cylinder having inlet and exhaust ports, a piston working in the cylinder, a plunger working in the cylinder back of the piston 90 and having side ports corresponding to the inlet and the exhaust ports, and an end port opening into the cylinder space back of the piston, an oscillatory valve carried by the plunger and having cavities which alternately lap the respective side ports and the end port of the plunger, and means for operating the plunger and its valve, so that during the exhaust stroke of the piston the exhaust side port of the plunger registers with the 100 exhaust port of the cylinder, and one of the cavities of the valve laps said exhaust side port and the end port of the plunger, the plunger traveling toward the piston and being at the limit of its travel in this direction at the end of the exhaust stroke, at which time the valve closes the end port of the plunger, and thence swings so that the other cavity of the valve laps the end port and the 110 inlet side port of the plunger, said inlet side port remaining in registry with the inlet port of the cylinder during the suction stroke of the piston, at the end of which stroke the plunger has moved to take its inlet side port out of registry with the inlet port of the cylinder, said inlet ports, as well as the exhaust ports remaining out of registry during the compression and firing strokes.

2. In an internal-combustion engine, a cylinder having inlet and exhaust ports, a piston working in the cylinder, a plunger working in the cylinder back of the piston and having side ports corresponding to the inlet and the exhaust ports, and an end port opening into the cylinder space back of the piston, a shaft, a pitman connection between the shaft and the plunger, the end of the pitman which is connected to the plunger having cavities which alternately lap the 120 125 130

respective side ports and the end port of the plunger, and driving means for the shaft, so that during the exhaust stroke of the piston the exhaust side port of the plunger registers 5 with the exhaust port of the cylinder, and one of the cavities of the valve laps said exhaust side port and the end port of the plunger, the plunger traveling toward the piston and being at the limit of its travel in this 10 direction at the end of the exhaust stroke, at which time the valve closes the end port of the plunger, and thence swings so that the other cavity of the valve laps the end port and the inlet side port of the plunger, said 15 inlet side port remaining in registry with the inlet port of the cylinder during the suction stroke of the piston, at the end of which stroke the plunger has moved to take its inlet side port out of registry with the inlet port of the cylinder, said inlet ports, as well 20 as the exhaust ports remaining out of registry during the compression and firing strokes.

In testimony whereof I affix my signature in presence of two witnesses.

GEORGE WALTER BROOKS.
